UNITED STATES PATENT OFFICE.

ZDENKO FREUND, OF NEWARK, NEW JERSEY, ASSIGNOR TO WILLIAM B. KERR AND COMPANY, OF NEW YORK, N. Y., A FIRM.

DESIGN FOR A BACK FOR HAND-MIRRORS OR SIMILAR ARTICLES.

SPECIFICATION forming part of Design No. 36,365, dated June 16, 1903.

Application filed May 18, 1903. Serial No. 157,736. Term of patent 7 years.

To all whom it may concern:

Be it known that I, ZDENKO FREUND, a citizen of the United States, residing at No. 120 Washington street, Newark, in the county of 5 Essex and State of New Jersey, have invented a new, original, and ornamental Design for the Back of a Hand-Mirror or Similar Article, as illustrated and shown in the accompanying drawing.

10 The figure of the drawing is a plan view of the back of a hand-mirror, showing my new design.

Having described my invention, what I claim as new, and desire to secure by Letters Patent, is—

15 The ornamental design for the back of a hand-mirror or similar article, as shown.

In testimony whereof I affix my signature in the presence of two witnesses.

ZDENKO FREUND.
